CONTROL APPARATUS

Howard Walker, Chicago, Ill., assignor to Bendix Radio Corporation, Chicago, Ill., a corporation of Delaware

Application April 18, 1938, Serial No. 202,682

5 Claims. (Cl. 172—239)

This invention relates to control apparatus and more particularly to motor powered apparatus which may be operated from a remote point. The improved apparatus may be used for actuating electrical switches or for effecting other kinds of control functions.

An object of the invention is to provide improved apparatus in which motor power is used to move the controlling member to some selected position and in which safeguards are provided for preventing movement of the control member beyond the selected position.

In motor powered control devices, it is a difficult problem to stop the controlling member at exactly the desired position, as the momentum of the motor tends to carry the movement on after the motor is deenergized, and this extra movement destroys the accuracy of control in the common control system. To overcome such disadvantage I provide drive mechanism by which the control member is driven only during spaced periods and in which the control member remains motionless during the intervening periods. With this construction it is possible to stop the motor during the intervening periods and thus eliminate any actuation of the control member due to the momentum of the motor and drive mechanism. As a further safeguard against the mechanism being moved on into the next period by the motor momentum, I provide means for throwing a reverse torque on the motor in case the mechanism should be moved by the force of momentum beyond a certain point in the intervening period.

I have found also that especially when the motor is geared to drive the control member at high speeds, this member will itself be moved on to an undesired position by its own momentum, even though it be unaffected by the motor momentum. To correct this objection and to prevent displacement from the selected position through any other cause, I provide locking means for maintaining the control member locked and immovable from the selected position except during the periods at which the driving mechanism is moving this member from one position to another. With such construction, the controlling member may be driven as rapidly as may be desired, and may be stopped at pre-selected positions with the positive guarantee that there can be no further movement to destroy the accuracy of the setting.

A further object is to provide improved apparatus in which the control member is rotatable, the driving means being adapted to rotate this

member intermittently in one direction to different angular positions corresponding with different control functions. Other objects and advantages will be apparent as the specification proceeds.

A preferred embodiment of the invention is illustrated in the accompanying drawings in which:

Figure 1 is a front elevational view of the improved device with the casing front removed; 10

Figure 2 is a plan view with the casing shown in section, the section being taken as indicated at line 2—2 of Figure 1;

Figure 3 is a rear elevational view showing one side of the rotary switch; 15

Figure 4 is a detail view of the switch shown in Figure 3, the view being taken as seen from line 4—4 of Figure 2;

Figure 5 is a detail view of the cam member employed for controlling the motor energizing circuits; and 20

Figure 6 is a schematic view showing the wiring arrangement.

As illustrated, A designates a casing or frame; B, a motor for supplying the necessary power 25 to actuate the mechanism; C, the movable control member by which the control functions are effected; and D, the drive mechanism through which the power of the motor is made effective to drive the control member to different positions corresponding with the control functions desired. 30

The frame or casing A may be of any suitable material, preferably metallic, and may be of any suitable form. As illustrated, casing A includes 35 a rear portion A₁ having forwardly turned edges, and a front portion A₂ having rearwardly turned edges, these portions being adapted to be fitted together to form an enclosure. The screws 10 which extend between portions A₁ and A₂ form 40 means for securing these portions in place.

At one end of the frame enclosure A is an opening 11 through which electrical connections may be made and which is convenient for inspection of the mechanisms contained inside. 45 At the other end of frame A the walls are formed into a cylindrical flange 12 into which is received one end portion of the electric motor B. This construction provides a convenient way of mounting the motor, though other mounting 50 means may be provided if desired.

The motor B is preferably an electric motor having two field windings, one of the windings being for excitation to produce rotation in one direction, and the other being for excitation to 55

produce rotation in the opposite direction. However, any suitable type of motor which is equipped with a circuit for setting up a reversing torque may be used. In the embodiment illustrated, 5 the motor shaft 13 is provided with a worm gear 14 which makes engagement with the toothed gear 15 keyed to the driving shaft 16. Through this engagement rotation of the motor is caused to produce rotation of the driving shaft. It is obvious that other means for connecting the motor in mechanical drive relation with the driving shaft may be provided if so desired.

The control member C is illustrated in the 15 form of a shaft having flattened sides and extending through the rear frame portion A₁. Within frame A is a hollow cylindrical sleeve 17 into which the end of shaft C is secured. This sleeve is equipped with a flange 18 on the front 20 side of which is secured the gear 20.

The gear 20 has its peripheral portion formed into the general shape illustrated more clearly in Figure 1 of the drawings. At spaced intervals along its periphery are the recesses 21 extending 25 radially inward and having curved walls. It will be noted also that the portions 23 between recesses 21 are also of curved contour so as to engage the surface of the cam 22 secured on shaft 16. Cam 22 has a circular periphery except for the flattened side 22^a, and operates through engagement with the tooth portions 23 to maintain gear 20 locked and motionless except when the side 22^a is adjacent these portions.

Secured on the drive shaft 16 just rearward of 35 cam 22 is the driving arm 24 carrying the forwardly extending pin 25. Arm 24 is aligned with the surface 22^a of cam 22 and is adapted to pass rearwardly of gear 20 as driving shaft 16 rotates, the pin 25 entering one of the recesses 21 to move gear 20. It will be observed that when pin 40 25 is moved to actuate gear 20, the side 22^a of the cam will have moved adjacent a peripheral tooth portion 23 so as to unlock the gear and leave it free to rotate; but as soon as pin 25 moves from the recess engaged, the circular surface of 45 cam 22 engages the next of tooth portions 23 to again lock the gear against rotation.

Mounted in any suitable way in the frame are the spring contact fingers 26^a and 26^b which normally maintain the contacts 26 closed, and also 50 the spring fingers 27^a and 27^b which normally maintain the contacts 27 open. The spring fingers 26^b and 27^a have their end portions extending over the driving shaft 16 and the lowermost of these, 26^b, is provided with a nose 28 which rides on the cam 40 secured on shaft 16.

The cam 40 is shown in detail in Figure 5 of the drawings. It has three arcuate peripheral surfaces each concentric with shaft 16 and of different radius. As shown in Figure 5, the cam surface 40^a is of smallest radius, the cam surface 40^b of medium radius, and the cam surface 40^c of largest radius. When the nose 28 rides on the surface 40^a, contacts 27 are open and contacts 26 are closed; when nose 28 rides on surface 40^b, the contacts 26 are open as well as the contacts 27; and when nose 28 rides on the surface 40^c, the contacts 26 are held open and contacts 27 are closed. As clearly shown in Figure 5, 65 the junction between each of these cam surfaces is rounded and smooth so that the nose 28 may pass easily from one cam surface to the other. Though as here illustrated each of the above described surfaces extend over substantially equal 70 parts of the cam periphery, this may be varied as

may be desired. It is essential only that there be three successive cam positions for producing the three conditions of the contacts 26 and 27 as above described.

Mounted on the rear side of frame A and having its rotor engaging the control shaft C, is the switch 50 shown more clearly in Figures 3, 4 and 6. On the rear side of this switch (Figure 3) the rotor is provided with three conductor segments 59 each of which has one tooth. The contact 51 mounted on the stator is adapted to make contact with the arcuate or inner part of the segment while the contacts 52 and 53 and 54 are adapted to make contact only with the tooth of a segment. On the other side of the switch (Figure 4) the rotor is provided with an annular conductor 60 having three spaced peripheral recesses 61. The contact 55 mounted on the stator is adapted to make continuous contact with the annular conductor irrespective of the peripheral recesses, but the contacts 56, 57, and 58 are adapted to contact conductor 60 except when in register with one of the three recesses. Contacts 56, 57, and 58 are connected around the edge of the switch stator to contacts 52, 53, and 54 respectively. Any other switching arrangement which is suitable for performing the necessary switching functions may be substituted for that above described.

As seen more clearly in Figure 6, one side of the supply line L is connected through the normal motor field 70 to the contact 55. From contact 55, the circuit may be traced to one of contacts 56, 57 or 58, then to one of points 76, 77, or 78 of the control switch 80 located at some remote point, and return to the other side of the supply line by way of ground.

An auxiliary circuit through field 70 may also be traced from the said side of the line through contacts 26 and return by way of ground. The circuit which when completed will produce a reverse torque on motor B, may be traced from the same one side of the supply line through reversing field 71, and through contacts 27 to contact 51; from contact 51 to one of contacts 52, 53 or 54, thence to one of points 76, 77 or 78 on switch 80; and return to the other side of the supply line by way of ground.

The control shaft A may have associated therewith any number of rotary switches 80 of a type similar to switch 50 which have their rotors secured to the shaft and have their stators mounted on some fixed support. The various electrical contacts on the stators of these switches may be connected to various circuit points in a radio receiver. With the contact points thus connected, it is clear that rotation of the member A operates to change the interconnection of these points, and in this way the improved apparatus is useful for conditioning a radio set for operation on a selected one of several frequencies. It will be understood, however, that other and different control functions may be achieved by different connection with the device being controlled.

Operation

With the apparatus in the position illustrated in Figures 1 and 6, the control member C is at rest and the control switch at the remote point is in its central position on point 77.

When the operator at the remote point turns switch 80 to point 78, this completes a circuit from one side of the supply line through the normal field 70, and contacts 56 and 78 to ground. Note that at this instant nose 28 is engaging 75

the intermediate cam surface 40^b and both contacts 26 and 27 are in open condition, thus rendering both the auxiliary and reversing circuits ineffective. Being energized through its normal field, the motor A begins to rotate and through the worm gear arrangement drives the shaft 16 in a direction which is counterclockwise as seen in Figure 1. Upon rotation of shaft 16, the cam surface 40^c is brought into contact with nose 28 and this closes contacts 27. This is of no effect, however, for at this time there is no path between contact 53 and ground, the remote control switch being on point 16.

As was before stated the control member remains locked in one position through the engagement between the cam 22 and one of the tooth portions 23 on gear 20 until the arm 24 has moved to bring pin 25 into contact with the walls of one of the recesses 21. After gear 20 has been moved through rotation of the arm 24 and at or just before the time the pin 25 has disengaged from the recess of gear 20, the rotor of switch 50 will have been turned to bring one of recesses 61 into register with contact 56 and the original energizing circuit will be broken; but before this time the lower cam surface 40^a will have moved into engagement with nose 28 and contacts 26 will thus have been closed to maintain the motor field 70 energized through the auxiliary circuit. After the pin 25 has left the recess in gear 20, the intermediate cam surface 40^b will come into engagement with the nose 28 to open contacts 26 and this operates to de-energize the normal field 70. Thus the motor is deenergized at a time after the control member has reached its new position and has been locked there. It is intended that the motor should coast to a stop while the intermediate cam surface 40^b is in engagement with nose 28, but if through motor momentum, movement should continue until the higher cam surface 40^c should come into engagement with nose 28, this will operate to close a circuit which energizes the reversing field 71. This latter circuit may be traced from one side 45 of the supply line through field 71 and contacts 27 to contact 51, and thence through contacts 52 and 16 to ground. This circuit will be completed only instantaneously, for once the circuit is completed, the reverse torque on the motor will quickly move the cam surface 40^c back out of contact with the nose 28 to again open this circuit.

If then, the operator at the remote point should move control switch 80 back to point 71, a circuit would be completed as before through the normal field 70 of the motor. When the next succeeding of recesses 61 in conductor ring 60 comes into register with contact 57, this original circuit is broken and energization of field 70 continued through the auxiliary circuit until cam 40 operates to open contacts 26 after which the motor is stopped as before. With switch 50 arranged as herein described, this latter position of the control member will be removed 120° from the position first considered. A consideration of other positions to which the control member may be moved discloses that there are three angular positions of this member which correspond with each of the three points on the control switch 80. In this particular embodiment it is contemplated that the shaft C may be arranged to actuate the rotors of switches having four settings which give the same electrical connections so that the control functions effected are repeated in each 120° of the shaft

movement, but the arrangement may be otherwise if so desired. For example, the gear 20 might be arranged with only four recesses instead of the twelve as shown; only one sector 59 might be used instead of the three as shown; ring 60 might have but one recess 61; and a control switch of four points might be used instead of the three-point switch as shown. In this example, each of the points of the control switch would have an individual control shaft position with which they correspond, and the operation of the motor deenergizing means for stopping the mechanism with the shaft in a selected position, would be the same as before explained. Variation in the number and spacing of the contacts on switch 50, the number and spacing of recesses in conductor ring 60, and in the number of recesses 22 in the gear 20, for varying the positions and angular movement of the control member C, must be considered with in the limits of this invention. However, regardless of the number of recesses in gear 20, it is important that the radial position of the pin or projection 25 bear such relation to the periphery of gear 20 that this gear is moved the desired angular distance at one turn of the member on which this pin is carried.

While I have shown but one embodiment of the improved device, it is obvious that many other embodiments might be constructed, and many changes may be made in arrangement and construction without departing from the spirit of the invention.

The foregoing detailed description has been given for clearness of understanding only, and no unnecessary limitations should be understood therefrom, but the appended claims should be construed as broadly as permissible in view of the prior art.

I claim:

1. Control apparatus of the character set forth comprising: a movable control member, an electric motor, drive means actuated by said motor for driving said member during periods in the operation of said motor but not during intervals between said periods, circuit means for energizing said motor for movement in one direction, cam means for deenergizing said motor after said member has been moved to a selected one of a plurality of positions and at a predetermined point in the operation of said motor during one of said intervals, and cam means operable subsequent to said first-mentioned cam means for energizing said motor for movement in a reverse direction whereby movement of said motor into the next of said periods of operation is prevented.

2. Apparatus as set forth in claim 1 in which each of said cam means have a common cam member which member is actuated by said motor.

3. Remote control apparatus of the character set forth comprising: a frame, a control shaft rotatably mounted in said frame, a gear member secured to said shaft and having peripheral recesses therein, an electric motor having a reversing field, a driving member rotatably mounted in said frame, said driving member having a projection adapted to engage said peripheral recesses in the gear member to rotate said gear member as said driving member is rotated, means connecting said driving member in mechanical connection with said motor, circuit means for energizing said motor for forward movement, means for deenergizing said motor after said member has been moved to a selected one of a plurality of positions and at a predetermined

- point in the operation of said motor during one of said intervals, said means including a cam member rotatable with said driving member, means operable only subsequently to the operation of said deenergizing means and in the event that said driving member moves on to a predetermined point in said interval for temporarily energizing the reversing field of said motor whereby movement of said motor into the next of said periods of operation is prevented, said means including said cam member, and locking means for holding said gear motionless during said intervals, said locking means including a cam member rotatable with said driving member.
- 10 4. In a selective control system having a plurality of control positions, a reversible electric motor, a shaft driven by said motor, an intermittent motion mechanism actuated by said shaft, a control member movable into said control positions and actuated by said mechanism, switch means for selecting any one of said control positions and energizing said motor, a cyclic switch

operated by said driven shaft, said cyclic switch having means for deenergizing said motor during its first cycle of operation after attainment of said selected control position and for establishing a reversing circuit upon overrun of said motor.

- 5 5. In a selective control system having a plurality of control positions, a reversible electric motor, a shaft driven by said motor, an intermittent motion mechanism actuated by said shaft, a control member movable into said control positions and actuated by said mechanism, switch means for selecting any one of said control positions and energizing said motor, a second switch operated by said driven shaft in timed relation with respect to said intermittent motion mechanism, and cam means associated with said second switch for deenergizing said motor after attainment of said selected control position and for establishing a reversing circuit upon overrun of said motor.

HOWARD WALKER.
